UNITED STATES PATENT OFFICE.

RALPH W. ATKINSON, OF PERTH AMBOY, NEW JERSEY, ASSIGNOR TO STANDARD UNDERGROUND CABLE COMPANY, OF PITTSBURGH, PENNSYLVANIA, A CORPORATION OF PENNSYLVANIA.

CABLE INSULATION.

Application filed May 12, 1923. Serial No. 638,572.

My invention relates to the construction of electrical cables, and particularly to the envelope of wrapped-on insulation which in such structures commonly surrounds the conducting core or cores. The object in view is the avoidance of a source of possible weakness in cable insulation, or at least in diminution of the liability to break-down under extreme conditions of service.

10 In the accompanying drawings I show diagrammatically, and with exaggeration of dimensions, and without those modifications in shape of the component parts of a cable incident to building, a cable so far built up as to illustrate my invention. Fig. I is a view partly in side elevation, partly in medial and longitudinal section of a cable built according to my invention; Figs. II and III are similar sectional views, drawn to 20 larger scale, showing the cable insulation alone in fragmentary manner, and more fully illustrating the invention. The planes of section of Figs. II and III are at an angle one to the other, and would so appear if plotted on a drawing of the cable in cross section. The body of the cable conductor itself is omitted from Figs. II and III, to make the showing simpler.

The insulation of an electrical cable commonly includes tape, formed perhaps of paper, or of fabric, or even of rubber, wrapped helically about the central core. The helix may be laid with the edges of successive turns spaced apart, or closely contiguous, or overlapping. The insulation value of the laminate structure so built up is greatest, of course, where the tape lies in continuity, layer upon layer; and this maximum insulation value is diminished at the seam which is formed at or between the adjacent edges of the successive turns. There spaces inevitably are found. And this is true whether the helix be laid in one or another of the alternative modes mentioned; and it is true, however small the spaces may be which are formed at the seam, and with whatever substance these spaces be filled—whether with a saturating and filling compound applied in liquid form, or with air or other gas under high or low pressure.

For certain manufacturing reasons, it is not always desirable to wrap the tapes of the entire envelope of insulation, all in the same

direction. That is to say, in the usual 55 cable-building operation, a number of tapes will be laid on in one direction, and, succeeding them, an additional number will be laid in reverse direction, and there may be several such reversals in the direction of "lay", in 60 the building up of the whole insulating envelope. When layers wrapped on in the same direction are superposed, the seams between the turns do not directly overlie one another; the seam of a superior layer lies 65 upon the continuous web of the tape of the inferior layer. But where the direction of the "lay" is reversed the seams in the superior layer will cross the seams in the inferior, and at recurrent points the condition of diminished insulating value at the seam due to the superposing of weak portions is more serious than where the gaps occur separately.

The choice of the thickness of tape is the 75 result of a compromise between desirable properties which are secured on the one hand by thick tape and other desirable properties which are secured on the other hand by thin tape. The going to an extreme in either direction, that is a thick tape or a thin tape, results in a substantial loss in the efficiency of the insulation as a whole.

A primary advantage of thick tape over 85 thin lies in its greater strength to resist tearing. Thin tape may be made to have high tensile strength, but even so, its strength to resist tearing is, relative to its thickness, low. Tearing strength is strength 90 to withstand twisting strains; tensile strength is strength to resist strains exerted in the plane of the material. In practice when the tape of a cable has suffered injury, the injury will generally be found to be at- 95 tributable, not to its lack of tensile strength, but rather to its liability to tearing. It may have been torn while being applied or it may have been torn under stress incident to the bending of the finished cable. Even if the thinner tape were proportionately to its thickness as strong to resist tearing as is the thicker tape, still thinner tape would be at a disadvantage, for the stresses of manipulation to which a cable necessarily is subject are the same, whether the tape be thin or thick; and when, added to that, it appears that thin tape is disproportionately weak,

the advantage of thick tape will be more clearly recognized.

A primary disadvantage of the thick tape as compared with the thin is in the thickness of this seam space. The cable designer then must in particular cases make choice between two evils; thick tape for other reasons preferable must when applied give relatively large seam spaces; thin tape, which gives 10 smaller seam spaces, is for other reasons inferior; and the designer must make a compromise. My invention reduces this difficulty, and allowing him to use for the most part the preferred thick tape, relieves him 15 of the difficulty of large seam spaces.

My invention lies in this, I use in those 20 wrappings which are superposed in spirals of the same direction relatively thick tapes, and in those wrappings where superposition is in reversed direction, relatively thin tapes. That is to say, I retain for the most part 25 thick tape with its peculiar advantage; but, at the point where the tendency to defect is enlarged, I use thin tape, and in so doing counteract that tendency. Stated in other 30 words, in a laminate insulation built up by applying tapes in helical wrapping, when it becomes desirable to reverse the direction of wrapping, the last tape of the underlying layer and the first tape of the overlying layer are of diminished thickness. Thus the otherwise enlarged spaces incident to reversal in direction of wrapping are kept small.

I find that in the practice of my invention the dilemma stated above is substantially avoided; I retain the advantage of thick tape without appreciable loss, and I avoid the evil of large seam spaces.

The invention is applicable, whatever be the particular mode of laying the helical wrapping.

Referring to the drawings, the conduction core of the cable is indicated at 1, an underlying layer of wrapped-on tape is indicated at 2 and an overlying layer at 3. These layers are wrapped on in opposite directions. The outermost wrap 4 of the underlying layer and the innermost wrap 5 of the overlying layer are shown to be of tape which, as compared with the remainder of the struc-

ture, is relatively thin. The term layer is here used arbitrarily to connote a portion of the whole envelope of insulation, a portion built up of tape applied in a succession 55 of turns, the direction of wrapping being uniform throughout the portion so particularly defined as a layer. The term layer is so employed in the ensuing claim.

The drawings show the invention applied 60 to tape wrapped on in open helix with the edges of successive turns spaced apart. It is manifest that the same point must be involved; however closely the edges may approach one another, and even in case the 65 edges overlap. Comparison of Figs. II and III will indicate how at recurrent intervals the relatively small spaces in layers 4 and 5 are superposed and increased in size. But the spaces in these particular layers are relatively small, and when superposed the aggregate size is still not too great. It will of course be remembered, but the observation should here be repeated, that the showing afforded in these drawings is diagrammatic, 75

In the building of a cable the number of superposed wraps in each direction may manifestly be increased indefinitely, beyond the few turns here shown diagrammatically. For the sake of simplicity of showing, the 80 number of layers and the number of reversals of wrapping are intentionally reduced to a few.

The invention manifestly is applicable to wrapped-on insulation generally, and in this 85 respect the showing of it in application to conductor is exemplary merely.

I claim as my invention:

An electrical cable including a conductor and a surrounding envelope of helically wrapped tape, the tape envelope being made up of superposed layers and the tape within each layer being laid in uniformly directed spirals and the tape of successive layers being laid in oppositely directed spirals, the 90 last tape of an inferior layer and the first tape of a superior layer being less in thickness than the tapes beneath and above. 95

In testimony whereof I have hereunto set my hand.

RALPH W. ATKINSON.
